Inventor

Ray W. Davis

By *Chasnow & Co.*

Attorney

UNITED STATES PATENT OFFICE.

RAY W. DAVIS, OF BROWNSVILLE, PENNSYLVANIA.

RUNWAY.

Application filed September 28, 1927. Serial No. 222,611.

This invention relates to runways, the primary object of the invention being to provide a runway of the portable type to facilitate the launching of an aeroplane 5 from the deck of a ship.

Another object of the invention is to provide a device of this character which may be readily and easily moved to its active position and one which may be readily taken 10 down when not in use.

A further object of the invention is to provide a runway made up of a plurality of sections which may be readily and easily disconnected or connected at the will of the 15 operator.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, may be made within the scope of what is claimed, without departing from the spirit of the invention. 25

Referring to the drawings:

Figure 1 is a side elevational view of a portable runway constructed in accordance 30 with the present invention, and showing the same in its operative position.

Figure 2 is a plan view thereof.

Figure 3 is a rear elevational view of the device.

Figure 4 is a longitudinal sectional view 35 through one of the sections of the runway.

Figure 5 is a transverse sectional view through a portion of the runway.

Figure 6 is an elevational view of the 40 plane elevating hook.

Figure 7 is a perspective view of the removable plate, at the lower end of the runway.

Referring to the drawings in detail, the 45 device includes a support 5 which is bolted or otherwise secured to the surface on which it is mounted.

Bearings indicated at 7 are on the support 50 5 and accommodate the shaft of the drum 8 on which the cables 9 that support the runway and form a part thereof, are wound. A crank indicated at 10 is mounted on one end of the drum and affords means whereby the drum may be rotated to wind the cables. The runway includes a plurality 55 of sections indicated generally by the

reference character 11, each section embodying a length of channel iron as clearly shown by Figures 4 and 5 of the drawings, there being provided tubular members 12 arranged 60 between the flanges of each section through which the cables 9 are extended when the runway is to be assembled for use.

Uprights 13 have their lower ends pivotally supported between the flanges 14 of the 65 securing plates 15, the flanges being provided with a plurality of openings 16 so that the uprights may be adjusted longitudinally of the securing plates to take up the slack in the runway. 70

The cables 9 are connected with the bar 17 that in turn is connected with the uprights 13 and as shown, a windlass 18 is provided on which the cable 19 is wound, the cable 19 being also connected by the bar 17 75 by means of the chains 20 so that as the cable 19 is wound on the windlass 18, the uprights 13 will be swung from a horizontal position to a vertical position as shown by Figure 1. 80

Bracing arms 21 also have pivotal connection with the uprights 13 at 22, the lower ends thereof resting in the notches 23 of the blocks 24 that are secured to the surface on which the device is mounted. 85

In order that the runway will be held rigid against lateral or swinging movement, under the action of the aeroplane moving thereover, lateral braces 25 are provided and act to hold the runway taut. 90

At the lower end of the runway is a removable plate 26 which is provided with a depending flange 27 to be hooked over a suitable securing mechanism forming a part of the support 5. Pulleys 28 are secured to one 95 of the sections of the runway between which pulleys the cable 29 operates, the cable 29 being provided with the plate 30 at one end, to which the hook 31 is pivotally secured, there being provided a pivoted keeper 32 in 100 the form of a yoke adapted to swing over the hook, to normally lock the hook against movement.

This cable 29 is used in moving an aeroplane from the surface on which the runway is positioned, to a position at the top of the runway. The reference character 33 indicates a hook that is connected with the cable 34, the cable 34 being comparatively short so that when it is desired to release the aeroplane, the cable 29 is slackened 110 after the propeller of the aeroplane has

been set in motion, to the end that a sudden pull on the hook 33 will move the keeper 32 to its inactive position, releasing the hook 31 and allowing the aeroplane to move over the runway so that it may be launched with facility.

It is to be understood that while the device is designed particularly for use on the decks of ships, the device may be efficiently employed on any supporting surface.

I claim:

1. A portable runway including a stationary supporting member, a drum on the supporting member, a plurality of cables wound on the drum, a plurality of runway sections removably secured to the cables, and means for elevating one end of the runway.
2. A portable runway including a stationary supporting member, a drum mounted on the supporting member, a plurality of cables adapted to be wound on the drum, runway sections including channel bars having openings through which the cables are threaded to connect the sections, and means for elevating one end of the runway.
3. A portable runway including a supporting member, a drum mounted on the supporting member, cables connected to the drum and adapted to be wound thereon, runway sections removably supported on the cables, pivoted uprights, a bar connecting the uprights at their upper ends and to which the cables are connected, means for moving the uprights to their active positions, and bracing arms for bracing the uprights in their active positions.
4. A portable runway including a stationary supporting member, a drum on the supporting member, a plurality of cables mounted on the drum and adapted to be wound on the drum, runway sections including inverted channel bars, said channel bars having openings, tubes connecting the openings of the channel bars and through which the cables extend, pivoted uprights to which the cables are connected, means for swinging the uprights to their vertical positions to elevate one end of the runway, and pivoted bracing members connected with the uprights for bracing the uprights in their vertical positions.
5. A portable runway including a supporting member, a drum mounted on the supporting member, cables wound on the drum, a plurality of inverted channel bars having their flanges contacting to provide a runway, said cables having connection with the channel bars to hold the channel bars together, uprights for elevating one end of the runway, means for moving the uprights to their active positions, and lateral bracing members for holding the runway against vertical movement.

In testimony that I claim the foregoing as my own, I have hereto affixed my signature.

RAY W. DAVIS.
